CLAIM

The ornamental design for a razor cartridge, as shown and described.

DESCRIPTION

FIG. 1 is a perspective view of a design for a razor cartridge of the present invention;

FIG. 2 is a front view thereof;

FIG. 3 is a back view thereof;

FIG. 4 is a top view thereof;

FIG. 5 is a bottom view thereof;

FIG. 6 is a left side view thereof;

FIG. 7 is a right side view thereof; and,

FIG. 8 is another perspective view thereof.

The razor cartridge is lined for the color blue and the interconnect member is lined for the color grey.

(Continued)

The broken lines illustrate portions of the razor cartridge and form no part of the claimed design.
